UNITED STATES PATENT OFFICE.

WILLIAM F. MAULICK, OF COLUMBIA, PENNSYLVANIA.

INCUBATOR.

SPECIFICATION forming part of Letters Patent No. 320,378, dated June 16, 1885.

Application filed April 17, 1884. (No model.)

To all whom it may concern:

Be it known that I, WILLIAM F. MAULICK, a citizen of the United States of America, residing at Columbia, in the county of Lancaster and State of Pennsylvania, have invented certain new and useful Improvements in Incubators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention consists in certain new and useful improvements in incubators, as will be hereinafter set forth and claimed.

In the accompanying drawings, forming a part of this specification, Figure 1 is a perspective view of my improved incubator. Fig. 2 is a detail perspective view of the heating devices employed. Fig. 3 is a detail perspective view of the lamp-supporting bracket. Fig. 4 is a perspective view of one of the egg-supporting trays. Fig. 5 is an inverted plan view of the said tray. Fig. 6 is an end elevation of said tray. Fig. 7 is a detail perspective view of the cut-off slide and operating devices therefor, and Figs. 8 and 9 are detail perspective views of the bracket devices for supporting the trays in position.

A represents a suitable case, which is mounted on legs, and provided in its top or upper side with a ventilator, *a*, and in its lower part of its opposite side with openings *a'*, above which on one of its sides are hinged the doors *B*, which may have panels of glass. This case is provided centrally with a transverse partition, which divides the same into two parts and provides a place to attach the shelf-holding means. The openings *a'* are covered and uncovered by a rectangular slide, *C*, which is constructed as shown in Fig. 7, and consists of the end piece, *c'''*, and the side pieces, *c*, at right angles thereto, which have slots or openings, *c'''* and are held in position by the diagonal brace-rod *c'*. At the point of junction of these brace-rod a plate, *c''*, is provided, against which bears the end of a screw-threaded rod, *d*, which passes through a screw-threaded block, *d'*, secured to the outer side of the case. This screw-threaded rod is provided at its outer end

with a crank-handle, *d''*. The slide *C* is secured within the case, so that by turning the crank-handle *d''* its slots or openings may be brought opposite the openings *a'* in the case and admit more or less air, as desired.

The heating apparatus consists of an upper rectangular tank, *D*, of substantially the same size as the inner portion of the case *A*, and the same is provided with an outlet-pipe, *e*, which extends through the top of the case. This tank is provided at opposite ends with pipes *E E'*, which connect the same with a second hollow rectangular tank, *F*, the inner edges of which are curved, as shown in Fig. 2. A vertical pipe, *G*, extends up and enters the tank *D* at each side at or about the center thereof, as fully shown in Fig. 2. After each pipe *G* enters the said tank it terminates in two diverging branches, *G'*.

To the lower vertical ends of the pipes *G* is secured a horizontal pipe having a T-connection, *g*, by means of which it is attached to the upper part of the boiler *H*. The aforesaid boiler is also connected to the tank *F* by means of pipes *I*, as shown. The boiler *H* is made in two sections, *h h'*, the lower section, *h'*, being provided with a central flue, while the upper part is connected thereto by short tubes, *h''*, as shown. The upper section, *h*, terminates in a cone, at the apex of which the lower end of the T-joint *g* is attached.

The circulation of the water in the tanks and boiler is indicated by arrows, and when the devices are in operation the tanks should be completely filled.

The lamp or heating device *K* is supported upon an adjustable shelf, *K'*, which is suspended under the boiler *H* by rods *K'''*, which are connected to each other at their lower portions by a spider, *K''*, having a central perforation. The shelf *K'* is provided with perforations, through which pass the rods *K'''*, and has attached at its central under portion an indented or perforated rod, *L*, which rod passes through the central perforation in the spider, and can be retained in different vertical positions by a set-screw. By means of this adjustable shelf the lamp can be raised or lowered.

Between the upper and lower sections of the boiler *h h'* is secured a perforated band, *M*, which serves to retain the heat between the

boiler and at the same time allow for the escape of the products of combustion.

To the inner sides of the case A and the partition therein are secured castings N, which have on their sides, adjacent to the walls, rack bars or projections n, with which engage castings N'. These castings are provided on one edge with a flange, n', to fit the recess s of the shelves S, and on the opposite side with hooks m, which engage with a rack of the casting N, thus forming a support for the shelves. The castings N' are provided with a hook m', which may engage with the edges of the casting N to prevent the same being withdrawn. The hook m' will always be held against the casting N when the shelves are within the case.

By means of the hooks m and rack-bars n the shelf-supporting casting N' may be adjusted to different heights within the casing.

The shelves S consist of a rectangular framework, two edges of which are provided with recesses s, and on its under side with boxes or frames S', which contain a series of suitably journaled sprocket-wheels, R. The frame is covered with wire-cloth, in which is cut a serpentine passage, r, between which passages are secured vertical guides r'. The chain T passes over the sprocket-wheels R, and is provided at suitable intervals with upwardly-projecting carriers t, with concave ends, which project through the passage r in the wire-cloth. The shaft of one of the sprocket-wheels of each tray depends sufficiently to permit the formation thereof into an operating crank-handle, R', as fully seen in Fig. 6.

The operation of my invention is as follows: When the tanks and boiler have been filled with water, which is heated by the lamp, a constant circulation will be maintained, and the water, as it rises through the pipes G, will be distributed at different points within the tank D, so that the whole of the same will be kept at an equal temperature and an equal

degree of heat will be maintained within the case. When the endless chain T is moved, it will carry with it the eggs, which are placed upon the shelf on their sides, and will turn the eggs as the chain is moved forward. The guides r' and curved carriers will prevent the eggs being moved from the groove.

I claim—

1. The combination, in an incubator, of the upper tank, D, the lower tank, F, the burner H, having upper and lower sections, h h', with connecting-tubes h'', central flue for the lamp, and perforated band M between the sections, and pipes E E' I G, the latter entering the upper tank and terminating in diverging pipes or branches G', substantially set forth. 60

2. The combination, in an incubator, of a case or receptacle provided with a series of openings on opposite sides extending horizontally, a rectangular slide having a series of slots, as described, and adapted to cover and uncover the openings in the case, and means of operating said slide, substantially as set forth. 65

3. In an incubator a shelf-supporting means, consisting of a casting, N, having rack-bars n, in combination with a casting, N', having hooks m, flange n', and retaining means m', substantially as shown. 70

4. The combination, in an incubator, of an egg-supporting tray, S, provided with a serpentine opening or passage, r, an endless chain located on the under side of the tray, as described, and a series of egg-carriers extending through said opening or passage, and actuating means for said chain, substantially as set forth. 75 80

In testimony whereof I affix my signature in presence of two witnesses.

WILLIAM F. MAULICK.
